(57) **ABSTRACT**

A detectable indicator (10) formed on a body (18), the indicator (10) comprising a deformable element (12), a safeguard (14) at least partially surrounding the deformable element (12) and an area (16) in the safeguard allowing access to the deformable element (12).

1
DETECTABLE INDICATOR

TECHNICAL FIELD

This invention relates to indicators and more particularly to a protected indicator that provides knowledge of the applicability of a part for further processing.

BACKGROUND ART

It is often necessary during the manufacture of articles to make certain that a particular part is available or properly located or positioned. To achieve this result, pieces have been marked with a prick mark, infrared labels, ink jet labels, etc. All of these prior techniques involved added parts and costs or suffered from an inability to consistently detect the infrared labels or ink jet labels.

It would be an advance in the art if a simple and effective locator could be provided.

DISCLOSURE OF INVENTION

It is, therefore, an object of the invention to obviate the disadvantages of the prior art.

It is another object of the invention to enhance the 25 manufacturability of parts.

Still another object to the invention is the provision of a detectable locator that is protected during pre-assembly operations.

These objects are accomplished, in one aspect of the invention, by a detectable indicator that comprises a deformable element; a safeguard at least partially surrounding the deformable element; and an area in the safeguard allowing access to the deformable element.

The indicator so provided is protected during all former 35 operations and is then deformed to indicate its availability for a subsequent operation.

BRIEF DESCRIPTION OF THE DRAWINGS

FIG. 1 is a perspective view of an embodiment of the 40 invention;

FIG. 2 is an elevational sectional view of the embodiment 45 of FIG. 1 with a part in moved position;

FIG. 3 is a perspective view of an alternate embodiment 50 of the invention; and

FIG. 4 is a similar view of the deformed indicator.

BEST MODE FOR CARRYING OUT THE
INVENTION

For a better understanding of the present invention, together with other and further objects, advantages and capabilities thereof, reference is made to the following disclosure and appended claims taken in conjunction with the above-described drawings.

Referring now to the drawings with greater particularity, there is shown in FIG. 1 a detectable indicator 10 that comprises a deformable element 12, a safeguard 14 at least partially surrounding said deformable element 12 and an area 16 in the safeguard allowing access to the deformable element 12.

The deformable element 12 in FIG. 1 comprises a tab 12a attached to a body 18 by a one-way hinge 12b. The one-way hinge can be in the form of a triangular slot 13 formed 65 partway through the tab 12a.

2

The safeguard 14 comprises a wall 14a up-standing from the body 18 and surrounding the deformable element 12 on three sides and providing an open side 14b, which open side 14b provides the area 16 that allows the access to the deformable element 12.

An alternate embodiment is shown in FIGS. 3 and 4 wherein the deformable element 12 comprises a heat-deformable rod 12c. The safeguard 14 in this instance comprises a circular wall 14c up-standing from the body 18 and 10 surrounding the deformable rod 12c on all four sides. The area 16 that allows access to the deformable rod 12c comprises an open top 14d opposite the body 18.

The detectable indicators thus provided are completely 15 protected during, for example, shipping operations; but are readily available for subsequent operations. After the sequence of operations that requires the indicator to be present, it can be deformed to eliminate it from further consideration.

In the embodiment of FIG. 1 this deformation can be 20 accomplished by a tool that enters the area 16 and deforms the element 12 by bending it over, as shown in FIG. 2.

Likewise, the deformable rod 12c can be deformed into the "mushroom-shape" shown in FIG. 4 by engaging it with a heated tool that enters through the open end 14d.

After deformation the elements have performed their necessary function by insuring that subsequent operations are ready to be performed.

The solution is simple and inexpensive and, once provided in the original design of the part, has no further impact 30 on the cost of the part. The safeguard protects the deformable element during shipping and operations that occur before the part is detected and yet allow its deformation once the part has been tested, verified or processed.

While there have been shown and described what are 35 present considered to be the preferred embodiments of the invention, it will be apparent to those skilled in the art that various changes and modifications can be made herein without departing from the scope of the invention as defined by the appended claims.

40 What is claimed is:

1. A detectable indicator that is protected during pre-assembly operations comprising:

a mechanically deformable element having a first position at a first stage of said pre-assembly;
a fixed, immovable safeguard at least partially surrounding said deformable element; and
an area in said safeguard allowing access to said deformable element for permanently moving said deformable element from said first position to a second position.

50 2. The detectable indicator of claim 1 wherein said deformable element comprises a tab attached to a body by a one-way hinge.

3. The detectable indicator of claim 2 wherein said safeguard comprises a wall up-standing from said body and 55 surrounding said deformable element on three sides and providing an open side, said open side providing said area allowing said access to said deformable element.

4. The detectable indicator of claim 1 wherein said deformable element comprises a heat-deformable rod.

5. The detectable indicator of claim 4 wherein said safeguard comprises a circular wall up-standing from said body and surrounding said deformable element on four sides and said area allowing said access comprises an open top opposite said body.
